(57) **CLAIM**

The ornamental design for a gun sling strap as shown and described.

DESCRIPTION

FIG. 1 is a side perspective view of the design of a gun sling strap showing the new design;

FIG. 2 is a right view thereof;

FIG. 3 is a right side elevational view of the gun sling strap shown in FIG. 1;

FIG. 4 is a bottom elevational view of the gun sling strap shown in FIG. 2;

FIG. 5 is a right-side elevational view of the gun sling strap shown in FIG. 2;

FIG. 6 is a left-side elevational view of the gun sling strap showing in FIG. 2; and,

FIG. 7 is a view of the gun sling strap mounted on a gun, with the gun shown in broken lines.

The broken lines showing of the applied hook and loop fastener in all views is for the purpose of showing portions of the gun sling strap that do not form a part of the claimed design. It being understood that the unclaimed hooks extend along the entire inner surfaces and the loops extend along the entire outer surfaces of the gun sling strap and in a repeating pattern as shown. The square pad on the short extension also includes same repeating pattern of the unclaimed loops with the same width of coverage and row spacing as the rest of the strap.
